UNITED STATES PATENT OFFICE.

WALTER D. HARRISON AND FRANK E. BEST, OF SEATTLE, WASHINGTON.

TIME-CONTROLLED SWITCH.

1,367,699.

Specification of Letters Patent.

Patented Feb. 8, 1921.

Application filed January 6, 1919. Serial No. 269,784.

To all whom it may concern:

Be it known that we, WALTER D. HARRISON and FRANK E. BEST, citizens of the United States, and residents of the city of

5 Seattle, county of King, and State of Washington, have invented certain new and useful Improvements in Time-Controlled Switches, of which the following is a specification.

10 Our invention relates to improvements in devices employed in connection with and actuated by a clock for the purpose of automatically controlling the application of electric currents for predetermined periods, at 15 the termination of which periods the current is automatically turned off.

One of our objects is to provide means for 20 adjusting the device to vary the term during which the current is used, both as to the duration of said term and the position of said term within the twenty-four hours, which compose the day. Other objects will be disclosed by a study of the following specification and the claims which terminate 25 the same.

In the accompanying drawings we have shown our invention embodied in constructions of the kind which are now most preferred by us.

30 Figure 1 is a diagram illustrating the manner of connecting our clock controlled switch mechanism with a series of devices to control the application of current thereto.

Fig. 2 shows the front face of the clock.

35 Fig. 3 is a front face view of the special mechanism found within the clock.

Fig. 4 is a section on line A—A of Fig. 3, limited mainly to the special mechanism employed.

40 Fig. 5 is an enlarged section on the line C—C of Fig. 3, showing the manner of operating the ratchet wheels.

Fig. 6 shows the rear end of the setting stem and the wing nut which is secured 45 thereto for hand operation thereof.

Fig. 7 is an enlarged edge view of a portion of the ratchet wheels and the pawl disk by which they are turned.

Fig. 8 is a section of the supporting and 50 frame members for the ratchet wheels, this being on the line E—E of Fig. 3.

Fig. 9 is a section on the plane of the plate 53, which carries the pawls.

Fig. 10 is a section of a metal cap which 55 incloses and forms a bearing for certain of the parts.

Fig. 11 is a face view and Figs. 12, 13 and 14, are sections showing the member which carries the conductive helix which forms the stationary contact member.

60

Figs. 15 and 16 are, respectively, a face view and a section on the line R—R of Fig. 16, of one of the special parts employed.

Figs. 17 and 18 are, respectively, an inner 65 side face view and a section on the line L—L of the member which carries the insulating helix.

Figs. 19 and 20 are, respectively, face and sectional views on the line M—M of the 70 member which carries one of the gears employed in setting adjustment of our device.

Fig. 21 is a section on line N—N of Fig. 3, showing gears 61 and 55.

Our improvements may be attached to or 75 combined with any form of time mechanism which is found suitable for actuating the same. We have herein shown it as combined with a clock of a standard type of construction, and we will describe it as combined with such a clock mechanism, it being, however, understood that such combination is only given as illustrative of one manner of employing our invention and not as in any way limiting its application to the particular mechanism or to the particular purpose described.

In carrying out our invention we employ 80 two helices, each of substantially a complete turn, these being of like radius and intermeshing after the manner of the threads of a double threaded screw. One of these helices constitutes a conducting element in an electric circuit and the other is an insulating element which acts as an insulating 85 shield for the first or conducting element.

In conjunction with these is a yielding contact or brush member which is caused 90 to move in a circular path in synchronism with and actuated from the clock mechanism, to contact with said helical elements, said brush member being also included in the circuit which is controlled by the device.

105 The conducting member of this combination, in the form of construction which is preferred by us, is shown separate from the other parts in Figs. 11, 12, 13 and 14. This member, indicated as a whole by the character 110 47, has a cylindrical shell or rim 470, a concentric bearing hub 471, a helical-

radially extending flange 472, which, together with the body of the member, forms a helical groove 473, and has its cylindrical shell notched from the opposite sides 5 to form a series of projecting teeth or fingers 474, by which it may be rotatively interlocked with its driving member.

The other, or complementary member, which carries the helical insulating shield, 10 is shown separate in Figs. 17 and 18, and is indicated as a whole by the character 46. This has a cylindrical ring 460, a flange 461, projecting radially therefrom and supplied with teeth by which the member is 15 turned, and the inwardly projecting helical flange 462, this preferably extending through an angle of 360°, or more. It also has a side or face projecting lug, or finger, 69, which is intended for rotative driving 20 engagement with a complementary lug, or finger, 68, carried by the member 60, shown separate in Figs. 15 and 16. Preferably the entire member 46 is made of an insulating material.

25 When assembled, as shown in Fig. 4, the two helical flanges 462 and 472, are screwed together so as to intermesh, after the same manner as the threads of a bolt and nut. The member 47 corresponds to the bolt and 30 46 to the nut. It may thus be seen that by turning these two members with relation to each other, the helical flange of the insulating member may be positioned to expose any angular extent of the conductive helical 35 flange 472 from 0° to 360°. The side or face of this flange, which is exposed to the rotating contact or brush member, is that which faces inward in the assembled device.

40 The metal or conductive member 47, is mounted for rotative adjustment upon an insulating member 50, which has a toothed flange 500, said member 50 being rotatively secured to the metal sleeve or thimble 49, 45 as by being a close or press fit thereon. The thimble 49 turns freely upon the metal journal pin 48, which latter is connected, as by wire 42, with one side of the circuit which is to be controlled. Pin 48 is shown as held 50 in fixed position by having flanges 490, 491, which engage opposite sides of a plate 14, which plate is preferably of insulating material. One of these flanges, 491, may be swaged or set out after insertion of the 55 pin in its hole in the plate.

A plate 51 has a hole in which the thimble or sleeve 49 is fixed, so that the plate and thimble must turn together. The insulating member 50 has a transverse slot which 60 receives the plate 51. Plate 51 has an end projecting beyond the periphery of this central hub of the insulating member 50. The radius of this projecting end is the same as of the helices 462 and 472, which are slightly 65 removed therefrom. This end has a spring

contact bar 52 secured by one end thereto, as by rivets 53. It is shaped as a sector of a circle, one end being loose and bent toward the helices 462 and 472, to contact therewith.

Mounted outside of and to turn upon the 70 fingers 474 of part 47, is a metal ring 60 which has a peripheral tooth or projection, 68, positioned to engage with lug or finger 69, of part 46. It also has fingers 70 positioned to enter openings 71 in the gear 670. 75 The fingers 70 are of somewhat less angular extent or width than the length of the slots 71, whereby there may be a certain amount of lost motion between them. This is in amount substantially equal to the combined 80 widths of the two lugs or fingers 68 and 69, for a reason which will be later pointed out.

The central hub 67 of gear 670 is in the form of a flat ring or short section of a 85 tube and fits within the fingers 474 of part 47. This gear is preferably made of an insulating material, to thereby prevent contact with the brush ring 52 with the fingers 474. The ring 60 has an exterior rotative 90 bearing within a cup-like member 41, which is secured to the frame plate 14, and also has one side of the circuit connected therewith. The two sides of the circuit are joined through the member 47, spring contact bar 95 52, plate 51 and stem 48. The portion of the twenty-four hour period during which the circuit is thus closed, will depend upon the angular adjustment of the two helices 472 and 462, relative to each other. 100

The relations of these parts to each other may be told from an inspection of their outer exposed faces, which would appear as in Fig. 2, in which one is shaped to indicate that its surface is of an appearance which 105 contrasts with that of the other.

By turning the insulating helix back until it is entirely withdrawn beneath the conducting helix, the circuit will be closed throughout the twenty-four hours. By adjusting the two helices so as to project the insulating helix to entirely cover the conducting helix, the circuit will be maintained open throughout the twenty-four hours. An 110 adjustment intermediate these extremes will 115 give a period of closing corresponding with the angular extent of the conducting helix which is exposed, this occurring during the hours corresponding with the position of this exposed segment relative to the scale of 120 hours.

The dial has a twenty-four hour system of numbering surrounding these parts, and a pointer or hand, 54, carried by the member 50 has its indications made to correspond 125 with the usual clock hands. The gear 500, which is at one end of member 50, meshes with an idler gear 550, mounted on shaft 55, this in turn meshing with gear 560, secured upon the shaft 56 of the hour hand. As 130

gear 500 is of double the diameter of gear 560, hand 54 and contact brush or spring 52, make one complete revolution in twenty-four hours.

5 The means for adjusting the two helices 462 and 472 is as follows. A stem 28 which is journaled alongside the stem 48, has secured thereon a disk 64, the latter being shown as having a sleeve 640, which closely
10 fits the stem 28. At opposite sides of disk 64 are mounted gear wheels 62 and 65, each of which, in addition to the spur teeth, have side facing ratchet teeth 620 and 650, respectively, as is shown in Fig. 7, which represents a section taken lengthwise the zone of the ratchet teeth.

15 The gear wheels 62 and 65 are mounted to turn free from the stem 28. A convenient manner of doing this is by journaling them on frame brackets 63 and 66, which are supported from one of the members of the clock frame, as from the plate 14. The disk 64 has spring tooth or pawl sections 641 and 642, cut therefrom or secured thereto, and
20 projecting toward opposite sides in position to engage respectively with the ratchet teeth 620 and 650, to thereby turn the gears 62 and 65. The pawls 641 and 642 face in opposite angular directions, so that the disk
25 64 may turn one wheel in one direction and the other in the opposite direction. The mounting of these wheels should present enough frictional resistance to prevent their turning backward; or this result may be
30 secured otherwise.

35 The gear wheel 65 meshes directly with gear wheel 67 which controls the position of the conducting helix 472. Gear wheel 62 is connected to turn gear wheel 461, but through
40 an idler 61, wherefrom and also due to the ratchet drive through which the gears 62 and 65 are turned, turning the stem 28 in one direction will turn one of the gears 670 or 461 in one direction, while turning the stem
45 in the opposite direction will turn the other of said gears 461 or 670 in the same direc-

tion. It is thus possible to adjust both helices through the same shaft.

By the use of the intermeshing helices, one being conductive and the other non-conductive, these being adjustable relative to each other, the period of electrical contact may be made any part of the twenty-four hours. By having both helices adjustable relative to their axis, the disposition or location of this period of contact within the twenty-four hours may be determined.

As stated above, the openings 71, through which the fingers 70 and 474 pass, exceed in width the width of the fingers by an amount equal to the combined widths of the lugs 68 and 69. If the lug 69 is started from one side of the lug 68 and brought through a revolution to the other side of this lug, it will not have completed a full revolution of 360° , and it is not desired to move the member 47 until this revolution is completed. Hence, after engagement of the lugs 68 and 69, they will move relatively to the member 47, by reason of the excess width of the openings 71, until the lug 69 has exactly completed a full revolution. The two helices and the indicating parts are then in their proper relative position.

What we claim as our invention is:

In an electric switch, a contact member movable in a circular path, a complementary conductive contact member extending within a like circular path, and an insulating member having a corresponding circular extent, a common adjusting member for both said last named members and independent means operatively connecting said adjusting member with said insulating member and with its complementary conductive member to adjust these by turning said adjusting member in respectively opposite directions.

Signed at Seattle, Washington, this 30th day of December, 1918.

WALTER D. HARRISON.
FRANK E. BEST.
